CLAIM

I claim the ornamental design for a case for mobile communications device, as shown and described.

DESCRIPTION

FIG. 1 is a front perspective view of a case for mobile communications device;

FIG. 2 is a rear perspective view of the case for mobile communications device of FIG. 1;

FIG. 3 is a front view of a case for mobile communications device of FIG. 1;

FIG. 4 is a rear view of a case for mobile communications device of FIG. 1;

FIG. 5 is a left side view of a case for mobile communications device of FIG. 1;

FIG. 6 is a right side view of a case for mobile communications device of FIG. 1;

FIG. 7 is a top view of a case for mobile communications device of FIG. 1; and,

FIG. 8 is a bottom view of a case for mobile communications device of FIG. 1.

The broken lines in FIGS. 1-8 having a dash-dash configuration depict environmental subject matter that forms no part of the claimed design. The broken lines in FIGS. 1-8 showing a dot-dash configuration represent a boundary of the claimed design.
